TIE OR CLAMP FOR BUILDING FORMS

Filed June 13, 1929

UNITED STATES PATENT OFFICE

HENRY HERBERT TOOGOOD, OF LOS ANGELES, CALIFORNIA

TIE OR CLAMP FOR BUILDING FORMS

Application filed June 13, 1929. Serial No. 370,571.

This invention relates to a tie or clamp for forms of that type used in building walls and other monolithic structures from cement concrete, and has for one of its objects to provide a novel, simple and highly efficient device of this character which may be manufactured and sold at a comparatively low cost and which will permit the forms to be erected in a comparatively short time and at the expenditure of comparatively little labor.

The invention has for a further object to provide a tie or clamp of the character stated which may be used in connection with forms of any thickness and configuration, which will permit a wide latitude in the size and nature of the materials from which the form is to be made, and which will permit the exact calculation of the number and the relative spacing of the ties or clamps necessary to resist the bursting strains to which a form of any particular size and shape will be subjected.

The invention has for a further object to provide a tie or clamp of the character stated which shall be adapted to be used in connection with forms of such configuration as to provide the wall with horizontal projections such as sill or string courses, plinths, cornices or copings, and in connection with forms of such configuration as to provide walls with vertical projections such as pilasters, piers and offsets.

The invention has for a further object to provide a tie or clamp of the character stated which shall be adapted to be used in connection with forms of that type adapted to form walls having one or both faces thereof battered, the tie or clamp permitting such walls to be maintained to the exact lines of the design by a simple adjustment of the parts of the tie or clamp.

The invention has for a still further object to provide a tie or clamp of the character stated which will permit all evidence of the use of the clamp to be easily and quickly covered up.

To attain the foregoing and other objects, the invention comprehends the provision of a tie or clamp embodying a convolute stem or rod, spacers engaged with the stem or rod

so as to permit them to be adjusted thereon by imparting a turning movement thereto, and nuts similarly connected to the stem or rod.

The invention is hereinafter more fully described and claimed, and illustrated in the accompanying drawings wherein:

Figure 1 is a view partly in horizontal section and partly in plan of a form having the various parts thereof secured in assembled relation through the medium of a tie or clamp constructed in accordance with my invention;

Figure 2 is a sectional view taken upon a plane extending vertically and centrally through a portion of the stem or rod and through one of the spacers;

Figure 3 is a sectional view taken on a plane extending vertically and centrally through a portion of the stem or rod and one of the nuts;

Figure 4 is a sectional view taken on the plane indicated by the line 4—4 of Figure 2;

Figure 5 is a view in end elevation of one of the nuts;

Figure 6 is a sectional view illustrating a slight modification of the tie or clamp;

Figure 7 is a sectional view illustrating a slightly modified form of the stem or rod;

Figure 8 is a view in end elevation of one of the spacers; and

Figure 9 is a plan view illustrating the tie or clamp adapted for use in connection with forms used in building hollow walls.

Referring in detail to the drawings, 1 designates the sides or sheeting, 2 the vertical studs, and 3 the wales of a form of well known structure and adapted to be used for building walls or other monolithic concrete constructions. The tie or clamp for the form comprises a stem or rod 4 which extends horizontally through the sides 1 and wales 3, spacers 5 connected to the stem or rod for the purpose of maintaining the sides 1 in properly spaced relation, and nuts 6 connected to the stem or rod for the purpose of holding it against any endwise movement with respect to the form.

The stem or rod 4 is made from a plurality of strands of wire. The wire strands 7 are

twisted to unite them in stem or rod forming relation and to provide the stem or rod with uniform convolutions which extend throughout the entire length thereof.

Any number of strands may be employed to form the stem or rod 4, and each strand may consist of a single element, as shown in Figure 4, or of several elements, as shown in Figure 7. The sides 1, studs 2 and wales 3 are provided with openings 8 for the passage of the stem or rod 4 which extends through the form to points outwardly beyond the wales.

The spacers 5 consist of conical castings, which are provided with interior convolutions conforming to and engaging the convolutions of the stem or rod 4. The spacers 5 are arranged upon the stem or rod 4 with their small ends arranged inwardly or in opposed relation. The sides 1 contact with the outer or large ends of the spacers 5 and are held in properly spaced relation by the spacers. The spacers 5 may be easily and quickly adjusted upon the stem or rod 4 so as to permit them to be arranged at the required distance apart, and they are secured in adjusted position by set screws 9 carried by them and engaging the stem or rod. The spacers 5 are provided in their outer or larger ends with radial grooves 10 so as to permit the use of a tool to effect their adjustment on the stem or rod 4.

The nuts 6 are also casted and are provided with interior inner convolutions for engagement with the convolutions of the stem or rod 4 so as to permit their adjustment on the stem or rod by imparting a turning movement thereto. The nuts 6 contact with the outer sides of the wales 3 and are provided at their inner ends with flanges 11 which are provided with openings 12 for the reception of nails 13 engaged with the wales and functioning to hold the nuts against rotation on the stem or rod 4.

The nuts 6 are provided with outer rectangular bosses 14 to permit them to be adjusted on the stem or rod 4 through the medium of a wrench.

From the foregoing description taken in connection with the accompanying drawings, it will be apparent that the tie or clamp may be readily applied during the erection of a form, that the spacers 5 may be easily and quickly adjusted on the stem or rod 4 to the points necessary to maintain the sides 1 in the required spaced relation, that the spacers may be easily and quickly locked in adjusted position by turning the set screws 9 inwardly into engagement with the stem or rod, that the nuts 6 may be easily and quickly adjusted on the stem or rod into contact with the wales 3, and that the nuts may be easily and quickly secured in adjusted position by driving nails through their flanges into the wales.

The stem or rod 4 may be of any desired

length, and it may be cut to the length necessary to adapt it for use in connection with the form. As the stem or rod 4 is made from intertwined strands of wire, and as the spacers 5 and nuts 6 are casted, the tie or clamp may be easily and cheaply manufactured.

When the wale consists of but a single member it is bored, as stated, for the passage of the stem or rod 4, and when it consists of two members, the members thereof are spaced apart a sufficient distance to allow for the passage of the stem or rod. When the nuts 6 are turned upon the stem or rod 4, all parts of the form are drawn into proper relation and are held in such relation by securing the nuts against accidental backward rotation through the medium of the nails 13.

As the spacers 5 are of conical formation and arranged on the stem or rod 4 with their small ends inwardly, they may be easily removed from the wall or other structure after the form has been taken down. To permit the removal of the form it is only necessary to turn the nut 6 off of the stem or rod 4. After the spacers 5 have been removed, the stem or rod 4 is cut off at points within the recesses formed in the faces of the wall or other structure by the spacers. The recesses may be filled with cement so as to prevent the corrosion of that portion of the stem or rod left within the wall or other structure.

If desired, the stem or rod 4 may be provided at one end with a loop 15, as shown in Figure 6, so as to obviate the necessity of the use of but one nut, and the looped end of the stem or rod is connected with the side of the form through which it extends by a pin 16.

To adapt the tie or clamp for use in connection with a form of that type used in building hollow walls or other structures, it is only necessary to increase the number of spacers and to arrange the spacers on the rod in the manner shown in Figure 9, wherein 1^a designates the sides of the form, 4 the stem or rod, and 5 the spacers, two spacers being employed for each side of the form and the spacers of each pair contacting with opposite faces of each side of the form. If desired, the spacers 5 may be provided at their outer ends with angular bosses to permit them to be adjusted on the stem or rod 4 through the medium of a wrench, the bosses being shown by dotted lines in Figure 8 and designated 17. Set screws 18 carried by the nuts 6 and engaging the stem or rod 4, hold the stem or rod against any turning movement with respect to the nuts.

When it is necessary to remove the entire stem or rod from the wall or other structure, a piece of pipe having detachable ends is used as a spreader and the stem or rod is pressed through this spreader. The convolutions or screw threaded elements of the stem or rod,

spacers and nuts are of long pitch variety so as to permit the rapid adjustment of the spacers and nuts.

While I have described the principle of the invention together with the structure which I now consider the preferred embodiment thereof, it is to be understood that the structure shown is merely illustrative and that such changes may be made, when desired, as fall within the scope of the invention as claimed.

I claim:—

1. A form tie or clamp including a stem or rod consisting of intertwined wire strands, the intertwisting of the strands uniting them and providing the stem or rod with screw threads extending throughout the entire length thereof, spacers having a spiral-shaped opening axially therethrough, and set screws mounted in said spacers whereby to hold the spacers in adjusted position on said strands.
2. A form tie or clamp including a stem or rod consisting of intertwined wire strands, conical spacers having inner screw threads engaging the wire strand, set screws carried by the spacers and engaging the stem or rod, and nuts having inner screw threads engaging those of the rod.
3. A form tie or clamp comprising a plurality of intertwined elements, the intertwisting of the elements uniting them and providing the stem or rod with screw threads extending throughout the entire length thereof, a cast metal spacer having inner screw threads engaging those of the stem or rod, a set screw mounted in said spacer and adapted to hold said spacer against rotation on said elements, and a cast metal nut having inner screw threads engaging those of the stem or rod.

In testimony whereof I hereunto affix my signature.

HENRY HERBERT TOOGOOD.
